UNITED STATES PATENT OFFICE.

MARTIN G. CARTER, OF LOS ANGELES, CALIFORNIA.

DESIGN FOR A TOY GENTLEMAN MONKEY.

Application filed January 8, 1923. Serial No. 4,835. Term of patent 14 years.

To all whom it may concern:

Be it known that I, MARTIN G. CARTER, a citizen of the United States, residing at Los Angeles, in the county of Los Angeles and State of California, have invented a new, original, and ornamental Design for Toy Gentleman Monkey, of which the following is a specification, reference being had to the accompanying drawing, forming part thereof.

The figure is a perspective view of a toy gentleman monkey, showing my new design.

I claim:

The ornamental design for a toy gentleman monkey, as shown.

Signed at Los Angeles, California, this 27th day of December, 1922.

MARTIN G. CARTER.
